Inventor.
Howard H. McGee,
By his Attorney, *Orrell H. Johnson*

UNITED STATES PATENT OFFICE.

HOWARD H. McGEE, OF WATERBURY, CONNECTICUT, ASSIGNOR TO THE GOODYEAR'S INDIA RUBBER GLOVE MANUFACTURING COMPANY, A CORPORATION OF CONNECTICUT.

FOUNTAIN-SYRINGE BAG.

Application filed September 16, 1920. Serial No. 410,614.

To all whom it may concern:

Be it known that I, HOWARD H. McGEE, a citizen of the United States, residing at Waterbury, county of New Haven, and

5 State of Connecticut, have invented certain new and useful Improvements in Fountain-Syringe Bags, of which the following is a full, clear, and exact description.

This invention relates to a fountain 10 syringe bag, more particularly to an integral connector therefor for the outside telescopic reception of an outlet tube.

Previously in the manufacture of fountain syringe bags it has been customary to 15 make the bag with an outlet extension with in which was telescopically received one end of a hard rubber connector, over the other end of which was telescoped the end of the outlet or nozzle supply tube.

20 This method of making the bag is relatively expensive, as a number of operations are required in the separate manufacture of the hard rubber connector and the latter must then be assembled with the finished 25 bag. A more serious objection is that the outlet end of the bag must fit very tightly around the connector in order to prevent leakage or the accidental withdrawal of the connector, hence in assembling the finished

30 bag and connector when the outlet of the bag is mechanically stretched in order to insert the connector, a certain percentage of the bags split at this point, entailing considerable waste. A still more serious objection 35 is that owing to this tight fit of the bag outlet with the connector the material of the bag is constantly under a considerable tension at this point, and as a result the bags split or crack at the outlet after a

40 relatively short period of use, thereby entailing the loss of the bag when it is otherwise in good condition. Another defect of the prior art construction is that as the hard rubber connector is relatively smooth 45 and is provided with the ordinary form of retaining shoulder there is not sufficient frictional resistance to the withdrawal of the supply tube therefrom and the tube therefore is liable to slip off.

50 An object of my invention is to provide a flexible receptacle of vulcanizable material with an integral connector for the outside telescopic reception of a flexible outlet tube.

55 Another object of my invention is to pro-

vide an improved construction of fountain syringe bag which will lengthen its life and impart uniform wearing qualities to all portions of the bag.

Still another object of my invention is 60 to reduce the number of parts and operations required in the manufacture of a fountain syringe bag and thereby cheapen its cost.

A further object is to provide a connector 65 between a flexible fountain syringe bag and its outlet tube which is formed of the bag stock and integral with the bag, but which is possessed of sufficient rigidity to allow the ready telescoping thereover of the flexible outlet tube.

A still further object is to provide a connector for the telescopic reception of a flexible tube, which will allow of the ready 70 telescoping of the tube thereover but which will afford a strong frictional resistance to the withdrawal of the tube.

For a detailed disclosure of the invention reference is had to the accompanying specification and drawings, in which latter— 80

Fig. 1 is an elevation of my improved bag and connector, and

Fig. 2 is a detail section on an enlarged scale showing the construction of the connector.

85 Referring to the drawings the numeral 1 represents a flexible rubber fountain syringe bag of any ordinary construction, having an integral connector thereon designated generally by the numeral 2. This connector is 90 formed by a cylindrical extension 3 of the bag stock having a reduced and tapered portion 4 and an enlarged end portion 5, the end portion adjacent the tapered portion 4 having a rearwardly inclined feather edged 95 shoulder 6. Within the connector 2 and integrally united therewith is a sleeve 7 of soft rubber stock, but the composition of which is such as to provide a relatively stiffer material than the bag stock.

100 In making the bag any usual form of core is used but it is provided with an extension which forms the outlet bore 8 of the finished bag, and the mold is also provided with an extension which in connection with the core 105 extension forms the connector 2. The sleeve 7 of stiffer stock is first slipped over the core extension, and the molding and vulcanizing process is then proceeded with in the usual manner, the bag stock flowing over and in- 110

tegrally uniting with the stock in the sleeve 7 during the operation.

To assemble the outlet or nozzle supply tube with the finished bag all that is necessary is to force the end of the tube over the connector 2 in the usual manner, the reinforcement 7 stiffening the bag stock sufficiently to permit this to be done without difficulty. As the soft rubber of the connector 2 is in direct contact with the inner wall of the soft rubber supply tube it offers a frictional resistance to the withdrawal of the tube much greater than that afforded by the prior hard rubber connector. In addition, upon any strain on the supply tube tending to withdraw it from the connector the frictional resistance of the under-cut shoulder 6 is such that it is dragged along with the tube, thereby expanding the shoulder and increasing the resistance to withdrawal.

It will be seen that by my invention a fountain syringe bag has been provided the material of which is not under excessive or unequal strain at any point, thereby preventing cracking or breaking at the outlet and insuring a life for this portion of the bag equal to or greater in length than that of the remainder of the bag, the number of operations required to form the finished bag and connector has been greatly reduced, thereby cheapening its manufacture, and by forming the connector of soft rubber and providing it with the inclined feather edged shoulder the liability of accidental withdrawal of the supply tube from the connector has been greatly reduced.

While a specific application of the invention has been shown and described it is evident that it may be used wherever it is de-

sired to form an integral connector for a flexible receptacle of vulcanizable material, and various changes may be made in the article within the scope of the appended claims.

Having thus described my invention, what I claim and desire to protect by Letters Patent is:

1. As a new article of manufacture, a fountain syringe bag having an integral soft rubber reinforced connector for the direct outside telescopic reception of a nozzle supply tube.

2. As a new article of manufacture, a fountain syringe bag having an integral connector for direct outside reception of a nozzle supply tube, said connector comprising an inner reinforcement of relatively stiff stock integrally united by vulcanization to an outer covering of the bag stock.

3. A flexible fountain syringe bag having an integral reinforced tapered connector nipple of the bag stock, and expansible means carried by the end of the nipple for frictionally resisting withdrawal of an outlet tube telescoped thereon.

4. A connector for flexible vulcanized tubing comprising an interiorly reinforced nipple of flexible vulcanized material tapering toward its end and provided adjacent the end with means for frictionally resisting withdrawal of a tube telescoped thereon.

5. A connector for flexible rubber tubing comprising a reinforced tapered soft rubber nipple provided adjacent its end with an enlargement having a rearwardly inclined feather edged shoulder.

Signed at Naugatuck, Conn., this 13th day of September, 1920.

HOWARD H. McGEE.
